UNITED STATES PATENT OFFICE.

ALBERT N. HENDERSON, OF BUFFALO, NEW YORK.

IMPROVEMENT IN LAMPS.

Specification forming part of Letters Patent No. 37,690, dated February 17, 1863.

To all whom it may concern:

Be it known that I, ALBERT N. HENDERSON, of Buffalo, county of Erie, and State of New York, have invented a certain new and useful Improvement in Lamps; and I do hereby declare the following to be a full, clear, and exact description thereof, reference being had to the annexed drawings, making part of this specification, wherein—

Figure 1 is a perspective view of my lamp, and Fig. 2 a vertical section of my burner.

The object of my invention is to produce a cheap lamp that will burn kerosene and kindred oils without a chimney, without smoke, and without unpleasant odor, as it consumes all the gas escaping from the oil.

C represents the body of the lamp, which may be made of any suitable material. B is a wick-tube, made in the ordinary way. This wick-tube I surround by another similar tube of larger size, A, so as to leave a space, without ascending air-currents, all around the wick-tube of the fourth of an inch, (more or less, according to the size of the lamp,) at the bottom of which I make small holes in the top of the lamp. This larger tube, A, is fitted into a socket, E, in the top of the lamp, so that said tube may be sunk to a level with the top of the wick-tube, or elevated a little above it, at pleasure.

I have found by repeated experiments that any surplus gas or oil emitted from the wick sinks into the vacant space D, thus isolated between these tubes, and thence through the small holes into the body of the lamp, except what rises into and is consumed by the flame, which at its base spreads out to the edge of the outer tube, and thus envelops and consumes gradually all the gas that rises from said isolated vacant space between the tubes. Thus I make a cheap lamp that gives a bright, clear flame without a chimney, economizing oil and consuming all smoke, gas, or unpleasant odor.

What I claim as my invention, and desire to secure by Letters Patent, is—

The combination of the said larger tube around the said wick-tube, so as to afford the said space without air holes between them, in connection with the said small holes connecting said space with the interior of the body of the lamp in the manner and for the purposes set forth.

In witness whereof I hereto set my hand this 3d day of February, A. D. 1863.

ALBERT N. HENDERSON.
